UNITED STATES PATENT OFFICE.

SIDNEY MILTON DUNCAN, OF CHATTANOOGA, TENNESSEE, ASSIGNOR OF ONE-HALF
TO E. G. ALLEY, OF CHATTANOOGA, TENNESSEE.

CARD-OILING MACHINE.

Application filed December 19, 1923. Serial No. 681,644.

To all whom it may concern:

Be it known that I, SIDNEY M. DUNCAN, a citizen of the United States, residing at Chattanooga, in the county of Hamilton and State of Tennessee, have invented new and useful Improvements in Card-Oiling Machines, of which the following is a specification.

This invention relates to textile machinery, particularly to attachments for carding machines, and has for its object the provision of novel means for oiling the aprons of the card.

An important object is the provision of an apron oiling device which is power driven and which operates to oil the aprons smoothly and uniformly so as to insure against hardness, the device operating entirely automatically and rendering unnecessary the usual stopping of the machine while oiling is carried out by the present method.

Another object is the provision of an oiling apparatus associated with both the upper and lower decks of aprons whereby they will all be efficiently oiled simultaneously.

Still another object is the provision of a device of this character which may be quickly and easily removed from one card and placed on another whenever such is desired.

Yet another object is the provision of an apparatus of this character which will operate to distribute the oil absolutely evenly and thus minimize the production of striped goods and eliminate the formation of the objectionable soft and fluffy strands in the roving.

Still a further object is the provision of a device of this character in which ample means is provided for adjusting the flow of oil so that it may be regulated to meet various requirements and to insure the maximum efficiency, the device being moreover a great time and labor saver as well as economizing in the use of oil while preserving the apron and preventing loss in the operation of the machine to which the device is applied.

With the above and other objects and advantages in view, the invention consists in the details of construction to be hereinafter more fully described and claimed and illustrated in the accompanying drawings, in which:

Figure 1 is a diagrammatic side elevation

of a card showing my oiling device associated with the upper and lower decks thereof.

Figure 2 is an end view on a larger scale showing one portion of the card and showing my device applied thereto, 60

Figure 3 is a view partly in elevation and partly in section showing the portion of the device associated with the upper deck of aprons. 65

Figure 4 is a cross sectional view on the line 4—4 of Figure 3.

Figure 5 is a longitudinal section through the roller device associated with the lower deck, 70

Figure 6 is a section on the line 6—6 of Figure 2,

Figure 7 is a section on the line 7—7 of Figure 5,

Figure 8 is a perspective view of the dog, 75

Figure 9 is a section on the line 9—9 of Figure 5.

Referring more particularly to the drawings, the numeral 15 designates a diamond threaded shaft, that is a shaft formed with 80 two sets of grooves extending spirally around it in opposite directions, and this shaft is any length required for any width of rub roll head. Revolubly engaged upon this shaft is a tube 16 which is formed of two 85 similar sections having their inner ends formed with flanges 17 secured by bolts 18. At the point where these flanges meet there is provided a hole 19 within which is engaged the shank of a dog 20 which is shown 90 in detail in Figure 8 and which has an arcuate laterally inclined head portion 21 operating within the thread of the shaft 15. The purpose of this dog will be hereinafter made apparent. Surrounding the tube or 95 sleeve 16 are two wooden rollers 22 which are recessed for the accommodation of the flanges 17 and bolts 18 and which are connected by metal straps 23 of any desired number, though in actual practice four 100 would be ample. These wooden rollers are covered with absorbent material, preferably plush, indicated at 24, this plush being glued or otherwise suitably secured in place.

The numeral 25 designates a pair of 105 standards or bearings through which pass the ends of the tube or sleeve 16 and secured through the upper portions of these standards is a pipe 26 which has its lowermost portion provided with perforations 27 and 110

which is provided intermediate its ends with a T 28 providing for attachment of an oil conducting pipe for leading oil to the pipe 26 so that the oil will subsequently pass out through the perforations 27 onto the plush 24 and be applied by the latter to the rub rolls or aprons of the carding machine. The ends of this pipe 26 are closed, as by means of suitable plugs or caps, and the pipe is secured with respect to the standards 25 by means of suitable nuts 29 and 30 threaded onto the pipe and engaging against opposite sides of each standard. The upper extremities of the standards 25 are formed with recesses 31 for a purpose to be described.

The numeral 32 designates a pair of up-standing L-shaped brackets which are formed with longitudinal slots 33 through which pass securing bolts 34 suitably secured to the frame of the carding machine and carried by these brackets are boxings 35 which constitute bearings for the ends of the threaded shaft 15. Suitably supported from the brackets 32 is an arm 36 which receives and holds a rod 37 which is the same length as the threaded shaft 15 and which is for the purpose of forming a brace and also for the purpose of supporting the weight of an oil cup 38 which feeds oil to the pipe 26 through a pipe 39 connected to the T 28. The pipe 39 is held in a boxing 40 that is made with a lower end, as shown at 41, carrying a roller 42 adapted to roll along the rod 37. The element 41 is provided with a retaining strip 43 at its lower end to prevent the apparatus from accidentally jumping off from the rod 37, and this member 43 is held in place by thumb screws 44 which are readily removable in case of necessity.

Associated with the oil cup 38 is an adjusting screw 45 for the purpose of regulating the flow of oil to the pipe 38 and this oil cup is also provided with a conventional cut off valve operated by a cam lever 46 which is for the purpose of stopping the flow entirely.

The above described mechanism is that which is associated with the lower deck of aprons. There is a slight modification of the structure used for oiling the upper deck. The numeral 47 designates an inverted T-shaped bracket which has the ends of its arms provided with screws 48 adapted to be threaded into the recesses or sockets 31 at the upper ends of the standards 25. The upstanding central portion 49 of the bracket 47 is formed with a slot 50 through which passes a clamping bolt 51 which likewise passes through a slot 52 in an upstanding arm 53 which has its upper end carrying a bearing 54 through which is journaled a shaft 55 carrying rollers 56 covered with plush 57. Suitably mounted with respect to these rollers is a perforated oil pipe 58

which is similar to the pipe 26 except that it is not provided with a T. Connected with one end of this pipe is a flexible hose 59 which is attached to a leather belt 60 by clasps 61 provided for the purpose of holding the hose taut and to keep it from mashing flat as it passes around guide pulleys 62, illustrated. To the end of the belt 60 is fastened a weight 63 for the purpose of holding the hose taut as it is pulled back and forth across the carding machine. Carried by the upper end of the hose is a standard type of oil cup 64 which is for the purpose of feeding oil through the hose to the pipe 58 from whence the oil will leak through the perforations onto a tin plate 65 which is so made and shaped that the oil from the pipe 58 can be transferred to the rollers 56 without it being necessary to place the pipe 58 above the center or on top of the rollers 56. The pipe 58 may thus be horizontally disposed entirely to one side of the rollers 56 and this arrangement is necessary for the reason that this portion of the apparatus is for oiling the upper deck, as the pipe if located as shown in the arrangement for oiling the lower deck, would be in the way. It will be noted that the support 66 which carries the pulleys 62 about which the belt and hose are respectively trained is provided with a clamp 67 for securing this rod to the frame of the carding machine.

Assuming that the device has been constructed and assembled as above described, it is installed on the carding machine as indicated and the various adjustments are regulated to bring the rollers 22 on top and between the rub rolls of either the lower or the upper deck. When it is desired to oil both the upper and lower rolls at the same time, the two portions of the apparatus are connected by means of the screws 48 engaging within the recesses 31. It is of course necessary that various details of adjustment must be initially gone through with to bring the various component parts of the device in proper relation with one another but without interfering with any of the parts of the carding machine, as for instance the hose mentioned would have to be arranged in a certain relation and would have to be of a certain specified length.

Assuming that everything has been adjusted and made ready, the oil cups are filled with suitable oil and the carding machine is started, after which the flow of the oil from the cups is regulated and the oil will drop down onto the rollers 22 and 56 and saturate the plush coverings thereof. As the apron turns they impart the same rotary speed to the oiling rollers, thus rubbing the oil onto the aprons. As the rollers 22 are turned the dog 20 has relative rotary movement with respect to the shaft 15 and this causes the whole apparatus to travel

along on the shaft 15 from one side to the other of the carding machine and in this way the entire width of the aprons will be oiled and rubbed.

5. From the foregoing description and a study of the drawings it will be apparent that I have thus provided a simply constructed and automatically operated oiling device for efficiently treating, that is rubbing and oiling, the rub rolls or aprons of a carding machine so as to place them and maintain them in the proper condition to insure the best quality of output from the card. The device will thus efficiently operate to reduce labor and time involved in manual rubbing of rolls, while at the same time it will greatly economize in the use of oil and prevent ruining material.

10 While I have shown and described the preferred embodiment of my invention, it is of course to be understood that I reserve the right to make such changes in the form, construction and arrangement of parts as will not depart from the spirit of the invention or the scope of the subjoined claims.

20 What is claimed is:—

1. An oiling device for the aprons of a carding machine, comprising supports adjustably secured upon the frame of the card, a shaft rotatably mounted upon the supports, rollers rotatable and slideable upon said shaft and bearing against the aprons of the card, and means for feeding oil onto said rollers.

25 2. An oiling device for the aprons of a carding machine, comprising supports adjustably secured upon the frame of the card, a shaft rotatably mounted upon the supports, rollers rotatable and slideable upon said shaft and bearing against the aprons of the card, and means for feeding oil onto said rollers, said means comprising a pipe supported in spaced parallel relation to the rollers and movable longitudinally therewith, and regulatable means for feeding oil to said pipe.

30 3. An oiling device for the aprons of a carding machine, comprising supports adjustably secured upon the frame of the card, a shaft rotatably mounted upon the supports, rollers rotatable and slideable upon said shaft and bearing against the aprons of the card, and means for feeding oil onto said rollers, said means comprising a pipe supported in spaced parallel relation to the rollers and movable longitudinally therewith, and regulatable means for feeding oil to said pipe including an oil reservoir permanently connected with the pipe, a pipe leading from the reservoir to said first named pipe, and a trolley-like support for said last named pipe.

35 4. Means for oiling the aprons of a carding machine comprising supporting brackets adjustably and detachably connected with

the frame of the card, bearings carried by said brackets, a shaft journaled in said bearings, rollers rotatable and slideable upon said shaft, means for supplying oil to said rollers, said rollers bearing against the aprons of the card, and means for moving the rollers and the oiling means bodily transversely of the aprons.

5. Means for oiling the aprons of a carding machine comprising supporting brackets adjustably and detachably connected with the frame of the card, bearings carried by said brackets, a shaft journaled in said bearings, rollers rotatable and slideable upon said shaft, means for supplying oil to said rollers, said rollers bearing against the aprons of the card, and means for moving the rollers and the oiling means bodily transversely of the aprons, said means comprising an automatically operated screw connection between the rollers and shaft, the rollers being driven by movement of the aprons.

6. Means for oiling the aprons of a carding machine comprising supporting brackets adjustably and detachably connected with the frame of the card, bearings carried by said brackets, a shaft journaled in said bearings, rollers rotatable and slideable upon said shaft, means for supplying oil to said rollers, said rollers bearing against the aprons of the card, and means for moving the rollers and the oiling means bodily transversely of the aprons, said means comprising a dog carried by the rollers and a shaft having a diamond thread engaged by the dog.

7. Means for oiling the aprons of a carding machine comprising a stationarily mounted shaft detachably associated with the frame of the card, standards engaged upon and slideable with respect to said shaft, rollers rotatable and slideable upon the shaft and engaging the upper deck of card aprons, means for feeding oil to said rollers, and means for moving the rollers transversely of the aprons, said means being driven by movement of the aprons.

8. Means for oiling the aprons of a carding machine comprising a stationarily mounted shaft detachably associated with the frame of the card, standards engaged upon and slideable with respect to said shaft, rollers rotatable and slideable upon the shaft and engaging the upper deck of card aprons, means for feeding oil to said rollers, means for moving the rollers transversely of the aprons, said means being driven by movement of the aprons, auxiliary supports connected with said standards, rollers journaled associated with said auxiliary supports and engaging the lower deck of card aprons, and means for supplying oil to said second named rollers.

9. Means for oiling the aprons of a carding machine comprising a stationarily mounted shaft detachably associated with

the frame of the card, standards engaged upon and slidable with respect to said shaft, rollers rotatable and slidable upon the shaft and engaging the upper deck of card aprons, means for feeding oil to said rollers, means for moving the rollers transversely of the aprons, said means being driven by movement of the aprons, auxiliary supports connected with said standards, rollers journally associated with said auxiliary supports and engaging the lower deck of card aprons, and means for supplying oil to said second named rollers, said second named oil feeding means consisting of a perforated pipe located adjacent the second named rollers, a conducting plate disposed below said pipe and leading to the periphery of the roller, a reservoir for oil, a flexible hose leading from said reservoir, and connected with the oil feeding pipe, and guide means for the hose.

10. Means for oiling the aprons of a carding machine comprising a stationarily mounted shaft detachably associated with the frame of the card, standards engaged upon and slidable with respect to said shaft, rollers rotatable and slidable upon the shaft and engaging the upper deck of card aprons, means for feeding oil to said rollers, means for moving the rollers transversely of the aprons, said means being driven by movement of the aprons, auxiliary supports connected with said standards, rollers journally associated with said auxiliary supports and engaging the lower deck of card aprons, and means for supplying oil to said second named rollers, said second named oil feeding means consisting of a perforated pipe located adjacent the second named rollers, a conducting plate disposed below said pipe and leading to the periphery of the roller, a reservoir for oil, a flexible hose leading from said reservoir and connected with the oil feeding pipe, and guide means for the hose comprising an adjusting support carrying pulleys, a strap engaged about

the pulleys and carrying a counterbalancing weight, and clasps carried by the strap and embracing the hose.

11. Means for oiling the aprons of a carding machine comprising rotatably and longitudinally movably mounted rollers bearing against and driven by the aprons, means for feeding oil onto said rollers, and means for constantly moving the rollers longitudinally while the aprons are moving.

12. Means for oiling the aprons of a carding machine comprising rotatably mounted rollers bearing against and driven by the aprons, oil feeding means for supplying oil to the rollers and means for automatically shifting the rollers longitudinally while the aprons are running whereby to bear against all portions of the aprons.

13. Means for oiling the aprons of a carding machine, comprising a longitudinally movable support, rotatable rollers carried by the support and bearing against and driven by the aprons, means for supplying oil to the rollers, and means constantly moving the rollers longitudinally while the aprons are running.

14. Means for oiling the aprons of a carding machine, comprising a movable carriage device carrying rollers engaging against the aprons, means for feeding oil to the rollers, and means constantly moving the rollers longitudinally in accordance with the movement of the apron.

15. The combination with a carding machine including aprons, of a supporting carriage device mounted upon the frame of the carding machine, journally supported rollers engaging the aprons, means for feeding oil to the rollers, means for shifting the carriage, and means operated by movement of the apron for constantly moving the rollers longitudinally whereby to contact with all surfaces of the apron.

In testimony whereof I, affix my signature.

SIDNEY MILTON DUNCAN.
